CIRCUIT INTERRUPTER

James D. Cobine, Rexford, and Newell C. Cook, Schenectady, N.Y., assignors to General Electric Company, a corporation of New York

Filed Sept. 24, 1959, Ser. No. 842,011

10 Claims. (Cl. 200—149)

Our invention relates to an improved circuit interrupter. While not limited thereto, the present invention relates particularly to surge voltage protectors for alternating current distribution systems and gas type circuit breakers or interrupters for such systems.

In surge voltage protectors for alternating current systems, suitably spaced electrodes are provided to form an arc upon the incidence of excessive voltage surges. Such voltage surges may occur on alternating current power system as the consequence of a lightning discharge. Such voltage surge may also result from a switching transient. Whatever the source of the voltage surge, it is essential that an arc be promptly established between the electrodes, that it be maintained until the voltage surge disappears, and that it does not restrike when the system voltage recovers.

An alternating current gas (usually air) circuit breaker or interrupter poses a similar operational problem. Here the average circuit opening operation involves separation of the electrode contact faces while current is flowing, and hence, the creation of an arc. The arc is frequently maintained for a very considerable portion of the alternating current half-cycle. It is usually not possible—and indeed it is frequently undesirable—to interrupt the arc prior to the next occurring current zero. However, when the instantaneous current does reach a zero (whether the first following electrode separation or some subsequent zero), it is important to assure positively that the arc is not restriken when the voltage recovers.

In accord with the present invention, the unusual voltage recovery properties of silicon tetrafluoride and the characteristics of metal silico-fluoride double salts are utilized to provide highly effective surge voltage protector and gas circuit breaker or interrupter operation. The silicon tetrafluoride gas is characterized by a very rapid recovery of dielectric strength following arcing. While the arc exists, the gas provides conduction carriers for the electric current. However, when the arc current flow goes to zero, this gas very abruptly loses its conducting capabilities and very quickly forms a medium of relatively high dielectric strength. In an actual surge voltage protector or circuit breaker constructed in accord with the present invention, the effective length of the arc through the silicon tetrafluoride gas is made of sufficient length to define a rate of electric strength recovery exceeding the rate of recovery of system voltage. This assures that the arc is not restriken.

Further in accord with the present invention, the silicon tetrafluoride gas is formed by the action of the arc itself upon a non-conducting metal silico-fluoride located within the zone of thermal influence of the arc. The required silicon tetrafluoride gas is thus formed by the play of the arc upon the metal silico-fluoride, this action serving to decompose the metal silico-fluoride into the silicon tetrafluoride. The particular metal silico-fluoride may be any one of a variety of metals. For commercial and other reasons cuprous silico-fluoride ($CuSiF_6$) is preferred. The silico-fluoride may be located on or be a part of the arcing surfaces of the electrodes, it may be a separate body within the zone of influence of the arc, it may be a component of the glaze used on an insulator over which the arc plays, or it may be otherwise located to respond to the arc by the production of silicon tetrafluoride.

2

In accord with a specific embodiment of the present invention, the interrupter is defined by electrodes located within a substantially enclosed chamber. If desired, the chamber can be completely enclosed and filled with a gas providing a particularly high normal dielectric strength. Alternatively, the enclosure may be incomplete and air may be used as the initial gas. In either event, the silicon tetrafluoride formed by the arc remains generally in the chamber after arc extinction. Over a subsequent period of time it recombines with the residual metal fluoride formed when the silicon tetrafluoride is generated. In substantial measure the metal silico-fluoride is thereby regenerated and the unit conditioned for further operations. In one embodiment of this form of the structure, the electrodes themselves are a repository of metal silico-fluorides so that the reformed metal silico-fluoride is on the electrodes and is necessarily physically located so as to be subject to the influence of the arc, and hence become the source of silicon tetrafluoride for further interruptions.

It is, therefore, an object of the present invention to provide an improved circuit interrupter utilizing the usual properties of silicon tetrafluoride.

A further object of the present invention is to provide a circuit interrupter using silicon tetrafluoride and in which the current interrupted generates the required silicon tetrafluoride gas.

Another object of the present invention is to provide a circuit interrupter using silicon tetrafluoride gas in which it is unnecessary to surround the arc-electrodes with silicon tetrafluoride gas in a gas-tight chamber.

Still another object of the present invention is to provide an improved circuit interrupter in which a metal silico-fluoride is exposed to arc action to produce silicon tetrafluoride gas.

Still another object of the present invention is to provide a circuit interrupter especially suitable for use as a surge voltage protector where ceramic insulating surfaces such as insulator strings are subjected to the thermal influence of the arc.

Yet another object of the present invention is to provide a circuit interrupter especially suitable for use with an air or other gas circuit breaker in which the arc initially formed between separating contacts is propelled against arc-quenching surfaces.

The novel features which we believe to be characteristic of our invention are set forth with particularity in the appended claims. Our invention itself, however, both as to its organization and method of operation, together with further objects and advantages thereof, will best be understood by reference to the following description taken in connection with the accompanying drawings, in which:

FIG. 1 is a diagrammatic view of a circuit interrupter of the expulsion type constructed in accordance with the present invention;

FIG. 2 is an alternative embodiment of the circuit interrupter of FIG. 1;

FIG. 3 is a view of an insulator string with arcing rings defining a surge voltage protector in accordance with the present invention; and

FIG. 4 is a cross-sectional view of an enclosed surge voltage protector constructed in accordance with the present invention.

Referring now to FIG. 1, there is shown in a somewhat diagrammatic view a circuit interrupter of the gas type. In the form shown, the interrupter is of the air-break expulsion type. In this type of interrupter, the arc is drawn into a narrow channel or tube composed of, or surfaced with, a material that emits gases under the influence of the arc to aid in extinguishing the arc. In the specific form of the interrupter shown, the upper electrode 1 is made of copper or other suitable material

and is connected by lug 4 to one conductor 5 of the connected electric system. The other electrode 2 is in the form of a finger. It is also of a suitable conducting material such as copper. Electrode 2 at its end 2a is rounded to be received in the mating cup-like recess 1a of the upper electrode 1 to form an effective current conducting path.

The electrode 2 is movably supported by suitable means (not shown). It is connected to a conductor 6 of the connected electrode system by the connector 7, which may be of any suitable form not interfering with the up and down movement of the electrode 2. In a typical application of an interrupter of this form, the conductors 5 and 6, together with the electrodes 1 and 2, may be in series with an electric system load. In such application, the actuating mechanism (which may include a fusible element) pulls the conductor 2 from the contact-making to the contact-breaking position of FIG. 1 in response to excessive load current.

As shown in FIG. 1, the sleeve 3 is embedded in and protrudes from the upper electrode 1. This sleeve has a longitudinal bore 8 which receives the movable electrode 2 with a small annular clearance space. Normally, this sleeve is made of a material that generates copious quantities of gas under the influence of an arc drawn as the electrode 2 is brought down out of contact with the electrode 1. This gas tends to serve as a coolant and to aid in quenching the arc.

In accordance with the form of the present invention shown in FIG. 1, the sleeve 3 has at least its inside surface including a silico-fluoride material. That is, a material that contains a metallic silico-fluoride. Such material may, for example, be incorporated in the material from which the entire sleeve 3 is made. Alternatively, it may be incorporated in a resin paint or coating that is applied to the inside surface of the sleeve and subsequently hardens. In still another construction, the sleeve 3 may be of ceramic material and the inner bore 8 coated with a glaze containing silico-fluoride material.

Many metal silico-fluoride double salts may be used as the silico-fluoride material. Cuprous silico-fluoride (CuSiF_6) is especially useful because it has a favorable ionizing potential and is commercially available at a reasonable price. Other suitable materials include calcium silico-fluoride (CaSiF_6), barium silico-fluoride (BaSiF_6), sodium silico-fluoride (Na_2SiF_6), ammonium silico-fluoride ($(\text{NH}_4)_2\text{SiF}_6$), and lead silico-fluoride (PbSiF_6). These and other metal silico-fluoride double salts have the characteristic of decomposing under the influence of the electric arc. The decomposition products include silicon tetrafluoride (SiF_4), a gas under the conditions of the arc.

Like all the other gases in the arc, the silicon tetrafluoride ionizes and thus provides conduction carriers for the current. However, this gas has the unusual characteristic of providing a very rapid dielectric recovery voltage upon arc interruption. In an exceedingly short time after arc quench, a space containing a substantial quantity of silicon tetrafluoride deionizes and defines a space of substantial dielectric strength. An apparatus such as that of FIG. 1 thereby is capable of withstanding a very rapidly increasing applied voltage following arc extinction and may be applied to an electric system with a rapid voltage recovery following a current interruption.

FIG. 2 shows an alternative form of the structure of FIG. 1. In this form the upper electrode 1 is impregnated with a silico-fluoride material. Since the arc plays upon the electrode surface, this material decomposes to generate silicon tetrafluoride in the same fashion above described with reference to sleeve 3. If desired, the movable electrode 2 could be so impregnated in lieu of or in addition to electrode 1. It is preferred that at least electrode 1 be so impregnated so that the silicon tetrafluoride

gas evolved will tend to sweep over the space of the arc before discharging into the atmosphere.

FIG. 3 shows a transmission line conductor 9 carried by support arm 10 through the insulator string and surge voltage protector 11. The insulator string is made up of a group of connected insulators of the conventional porcelain type capable of sustaining the weight of the conductor 9. These are glazed with a material containing a silico-fluoride double salt, such as cuprous silico-fluoride. The arcing rings 13 are provided to form points of comparatively high electric field gradient between which the arc is initially struck in the event of an over-voltage on the line conductor 9.

In the event of an arc between the arcing rings 13, FIG. 3, the arc quickly envelops the insulators 12 and plays upon them. Silicon tetrafluoride evolves from the glaze on the insulators 12 under this action of the arc. The arcing space is thus occupied by silicon tetrafluoride gas and rapidly recovers its dielectric strength when the surge voltage disappears and the current zero takes place.

FIG. 4 shows still another embodiment of the present invention as applied to a surge voltage protector. In this instance, a pair of electrodes 15 are located in spaced relationship in the envelope 14 and have hook portions 16 outside the envelope for attachment to the circuit terminals to be protected. The envelope 14 is of any suitable insulating material defining a closed space. Either the electrodes 15 or some other portion of the unit subjected to the influence of the arc is impregnated or coated with a metal silico-fluoride double salt, such as cuprous silico-fluoride. In the event of a voltage surge, arcing takes place between electrodes 15, the metal silico-fluoride decomposes to form silicon tetrafluoride, and when the current is ultimately interrupted the silicon tetrafluoride defines a space of rapid dielectric strength recovery to withstand the system recovery voltage applied between the electrodes.

The closed device of FIG. 4 is essentially completely self-regenerating. When the arc is interrupted, the silicon tetrafluoride in the container envelope begins a process of reuniting with whatever metal it contacts. In a structure similar to FIG. 4, where essentially all of the exposed metal is also subjected to the arc, essentially all the resulting metal silico-fluoride double salt becomes available to generate silicon fluoride upon the next arc interruption. This regenerative feature is provided to a substantial degree in structures like those of FIGS. 1 and 2, where a substantial quantity of the silicon tetrafluoride recombines with exposed residual electrode materials. It is most effectively obtained, however, in a completely closed system such as that of FIG. 4.

While silicon tetrafluoride provides a rapid dielectric strength recovery, the ultimate dielectric strength of this gas is of the same order of magnitude as air. In a closed device such as that of FIG. 4, the ultimate dielectric strength of this gas is of the same order of magnitude as air. In a closed device such as that of FIG. 4, the ultimate dielectric strength can be somewhat increased by incorporating a gas of greater dielectric strength. One such gas is sulfur hexafluoride (SF_6). With a gas of the type in the envelope 14, the normal breakdown strength of the protector is determined by the dielectric strength of this gas and the rate of dielectric strength recovery following arc interruption is determined largely by the action of the silicon tetrafluoride.

If desired, the envelope 14 of FIG. 4 may be provided with a vent to prevent excessive pressure buildup. Some silicon tetrafluoride will tend to escape through such vent, but to a considerable degree the self-regenerating feature of the structure of FIG. 4 is retained.

In any of the devices made in accordance with the present invention it is necessary that the quantity of silicon tetrafluoride evolved to be sufficient in relation to the arcing space to provide the necessary dielectric strength. That is, when the arc is interrupted, the silicon

tetrafluoride must be so located that the subsequent system voltage recovery does not at any time exceed the dielectric strength available along any complete path between the electrodes. This operation is attained by using sufficient metal silico-fluoride double salt exposed to the arc to create an ample quantity of silicon tetrafluoride within the arc-space defined by the separated arc-electrodes.

It will be noted that in each of the devices here shown and described a pair of spaced electrode faces are provided between which an arc extends prior to interruption. The metal silico-fluoride is located on some portion of the mechanism exposed to the action of the arc. As shown by the respective embodiments, the location of the silico-fluoride material may be varied as desired so long as it is acted upon by the arc.

While we have shown and described particular embodiments of the present invention it will, of course, be understood that various modifications and alternative constructions may be made without departing from its true spirit and scope. The invention may, for example, be applied to fuses for high voltage interruption, air circuit breakers where the arc is magnetically or otherwise driven onto deionizing means such as arc-chutes and the like (which may include a non-conducting metallic silico-fluoride double salt to generate silicon tetrafluoride) and in other similar applications. We therefore intend by the appended claims to cover all such modifications and alternative constructions as fall within their true spirit and scope.

What we claim as new and desire to secure by Letters Patent of the United States is:

1. A circuit interrupter comprising in combination: means defining a substantially enclosed chamber; a pair of spaced electrodes within the chamber defining an arc-space to be spanned by an arc prior to interruption; and means located within the zone of thermal influence of said arc and containing a metal silico-fluoride which upon heating by said arc generates silicon tetrafluoride gas that momentarily occupies said arc-space to provide a medium of rapid dielectric strength recovery upon arc extinction, the gas further recombining with residual material within the chamber over a period of time to regenerate metal silico-fluoride and to condition the interrupter for future interruptions.

2. A circuit interrupter comprising in combination: means defining a substantially enclosed chamber; and a pair of spaced electrodes within the chamber defining an arc-space to be spanned by an arc prior to interruption, at least one of the electrodes defining an arcing surface and containing a metal silico-fluoride which upon heating by said arc generates silicon tetrafluoride gas that momentarily occupies the arc-space to provide a medium of rapid dielectric strength recovery upon arc extinction, the gas further recombining with the residual electrode material over a period of time to regenerate metal silico-fluoride and to condition the interrupter for future interruptions.

3. A circuit interrupter comprising in combination: means defining a substantially enclosed chamber; means including a pair of spaced electrodes with arcing faces defining an arc-space to be occupied by an arc prior to interruption, said means defining substantially the only exposed metal in the chamber and having at least a region adjacent one face comprising a metal silico-fluoride material which upon heating by said arc generates silicon tetrafluoride gas that momentarily occupies the arc-space to provide a medium of rapid dielectric strength recovery upon arc extinction, the gas further recombining with the residual material of said means over a period of time to regenerate metal silico-fluoride and to condition the interrupter for future interruption.

4. A surge voltage protector comprising in combination: a pair of spaced electrodes with arcing faces defining an arc-space to be spanned by an arc prior to interruption; and means located within the zone of thermal influence of the arc and including a metal silico-fluoride material which when exposed to arc current flow generates silicon tetrafluoride gas that momentarily occupies the arc-space to provide a medium of rapid dielectric strength recovery upon arc extinction.

5. A surge voltage protector comprising in combination: a pair of spaced electrodes defining an arc-space between which an arc is struck upon application of predetermined surge voltage; and means located within the zone of thermal influence of the arc and including a metal silico-fluoride material which when exposed to arc current flow generates silicon tetrafluoride gas that momentarily occupies the arc-space to provide a medium of rapid dielectric strength recovery upon arc extinction.

6. A surge voltage protector comprising in combination: a pair of spaced electrodes defining an arc-space between which an arc is struck upon application of predetermined surge voltage; and insulating means sustaining the electrodes in spaced relation and located within the zone of thermal influence of the arc, said insulating means including surfaces having a metal silico-fluoride material which when heated by arc current flow generates silicon tetrafluoride gas that momentarily occupies the arc-space to provide a medium of rapid dielectric strength recovery upon arc extinction.

7. A current interrupter comprising in combination: a pair of spaced electrodes with arcing faces defining an arc-space to be spanned by an arc prior to interruption, at least one of the arcing faces including a metal silico-fluoride material which when heated by arc current flow generates silicon tetrafluoride gas that momentarily occupies the arc-space to provide a medium of rapid dielectric strength recovery upon arc extinction.

8. A circuit interrupter comprising in combination: a first means defining an electrode face; a second means defining an electrode face; and third means supporting said first and second means in spaced relation to define an arc-space to be occupied by an arc prior to interruption, at least one of said means having portions exposed to the action of the arc and including a metal silico-fluoride.

9. A circuit interrupter comprising in combination: a first means defining an electrode face; a second means defining an electrode face; and third means supporting said first and second means in spaced relation to define an arc-space to be occupied by an arc prior to interruption, at least one of said means defining portions containing cuprous silico-fluoride and exposed to the action of the arc.

10. A circuit interrupter comprising in combination: a first means defining an electrode face; a second means defining an electrode face; and third means supporting said first and second means in spaced relation to define an arc-space to be occupied by an arc prior to interruption, at least one of said means including portions glazed with a material including a metal silico-fluoride and exposed to the action of the arc.
